UNITED STATES PATENT OFFICE.

HUBERT C. HART, OF UNIONVILLE, CONNECTICUT.

POULTRY-ROOST.

1,165,252.

Specification of Letters Patent. Patented Dec. 21, 1915.

Application February 18, 1915. Serial No. 9,034.

To all whom it may concern:

Be it known that I, HUBERT C. HART, a citizen of the United States, residing at Unionville, in the county of Hartford and State of Connecticut, have invented certain new and useful Improvements in Poultry-Roosts, of which the following is a specification.

This invention relates to poultry-roosts, 10 the object of the invention being to provide an article of this character by which the droppings deposited by the poultry during roosting, can be disposed of in an effective, easy and cleanly manner.

15 In the drawings accompanying and forming part of the present specification I have shown in detail one of the several convenient forms of embodiment of the invention which to enable those skilled in the art to practice 20 the same will be set forth fully in the following description. I do not restrict myself to this showing; I may depart therefrom in several respects within the scope of the invention defined by the claims following said 25 description.

Referring to said drawings: Figure 1 is a perspective view of a poultry-roost involving my invention. Fig. 2 is a plan view of the same, with parts broken away. Fig. 3 is 30 a detail of a scraping-member.

Like characters refer to like parts throughout the several views, which it will be noted are on different scales.

It is the custom to provide sheds or other 35 suitable buildings in which are mounted roosting members, such for instance as rods, on which the poultry roost. Their droppings are deposited on the floors of the sheds and at more or less regular intervals are 40 collected in barrels or other suitable receptacles. This entails some labor and time. By virtue of my invention I overcome these obstacles.

My apparatus comprises a roosting member 45 of suitable kind, such for instance as a rod, and a movable member for catching the droppings of the poultry occupying said roosting member. The movable member in question may be of any desirable nature, a belt, such as one of "endless" type, satisfactorily answering in this respect.

With the foregoing general observations I will now refer more in detail to the structure shown.

55 The framework for supporting the differ-

ent parts of the device may be of any suitable kind, that shown comprising the substantially duplicate frame members or uprights 2 and 3 of approximately inverted frusto-V form. There is provided a roosting member and the rod 4 meets the desired conditions; said rod also serves to tie together the two frame members 2 and 3, the ends thereof being rigidly connected in some suitable manner with the upper horizontal 60 or transverse portions of said frame members practically centrally of the length thereof.

In conjunction with the roosting member of whatever nature the same may be, there 70 is a movable bottom or dropping-receiving member and the endless belt or band 5 is quite satisfactory in this respect. Said belt is received upon the two drums 6 and 7 fastened suitably to shafts as 8 sustained for 75 rotation by bearings as 9 rigidly carried by the outer sides of the two frame members at proper points in the height thereof. The upper run (shown as horizontally disposed) 80 of said belt presents the dropping-receiving portion thereof, being located in parallelism with and below the rod 4 which as illustrated is situated practically centrally of the transverse extent of said belt so as to insure the droppings falling onto the belt regardless of the way in which the poultry on the 85 rod 4 face. It will be obvious that by causing the droppings to fall upon the belt or its equivalent, that the former do not pass onto the floor or its equivalent, of the shed, 90 by reason of which said floor can be kept in a clean condition.

I prefer to provide a positive connection between the two drums or rolls 6 and 7; that is I do not rely upon the friction between the two drums and the belt for transferring motion from one drum to the other. This means may vary radically as to kind, although sprocket gearing as will herein-after appear performs the function properly. 100 By shifting the belt different portions thereof are brought under the roosting member 4. As will hereinafter appear I provide in connection with the belt 5 or analogous part, a suitable scraper for positively removing the droppings from that part of the belt which has been in use for a certain time, for instance overnight, the belt when thus operated bringing under the roosting member a clean area. 105

As shown the shafts 8 have fastened thereto sprocket wheels 9' connected by the sprocket chain 10, one of said shafts such as that shown in the foreground in Fig. 1 and at the right in Fig. 2, having a suitable operating member as the removable hand crank 10'. It will be obvious that on the proper manipulation of said hand crank, the upper run of the belt can be moved in the direction of the arrow to present a fresh portion of the belt under the roosting member or rod 4.

The scraper may be of any suitable nature, the plate 11 answering satisfactorily in this regard. Said plate as represented is notched as at 12 to receive the drum 6 being fastened in some suitable manner to the frame member 2, the lower wall of the notch or opening 12 acting as the operative part 20 of the scraper and acting against the outer surface of the belt 5 while said belt is on said drum 6, by reason of which the scraper can secure a proper and substantial bearing against the belt. After the poultry have 25 roosted the two runs of the belt will be reversed and as said belt is operated the scraper 11 will positively remove all adhering matter from the belt, the particles thus taken off the belt falling into a suitable receptacle, such as the box 13 placed under the scraper 11.

What I claim is:

1. The combination of two separated frame members of approximately inverted frusto-V-form, a rod connecting the transverse portions of the frame members to tie said frame members together, said rod constituting a poultry roosting member, rollers supported for rotation by the frame members, and a belt around the rollers below 40 the rod, the belt extending through the frame members.

2. The combination of two separated frame members of an approximately inverted frusto-V-form, a rod connecting the transverse portions of the frame members to tie said frame members together, said rod constituting a poultry roosting member, rollers having shafts supported for rotation by the sides of the frame members, a belt around the rollers, below the rod, the belt extending through the frame members, sprocket wheels rigid with the respective shafts, and a sprocket chain connected with the sprocket wheels.

In testimony whereof I affix my signature in presence of two witnesses.

HUBERT C. HART.
